UNITED STATES PATENT OFFICE

117,193

DESIGN FOR A VISCOSIMETER

Alexander I. Newman, Chicago, and Walter Van Guilder, River Forest, Ill., assignors to Precision Scientific Company, Chicago, Ill., a corporation of Illinois

Application July 13, 1939, Serial No. 86,000

Term of patent 7 years

To all whom it may concern:

Be it known that we, Alexander I. Newman and Walter Van Guilder, citizens of the United States, residing respectively at Chicago, in the county of Cook and State of Illinois and River Forest, in the county of Cook and State of Illinois, have invented a new, original, and ornamental Design for a Viscosimeter, of which the following is a specification, reference being had to the accompanying drawing, forming part thereof,

Figure 1 is a front perspective view of a viscosimeter showing my new design.

Fig. 2 is a rear elevation, on a reduced scale, of the same.

We claim:

The ornamental design for a viscosimeter, substantially as shown.

ALEXANDER I. NEWMAN.
WALTER VAN GUILDER.
